UNITED STATES PATENT OFFICE.

HELENA J. TITUS, OF NEW YORK, N. Y.

DESIGN FOR A HEXAGONAL COSMETIC BOX.

Application filed February 7, 1927. Serial No. 20,641. Term of patent 7 years.

To all whom it may concern:

Be it known that I, HELENA J. TITUS, a citizen of the United States of America, residing in the city, county, and State of New York, have invented a new, original, and ornamental Design for a Hexagonal Cosmetic Box, of which the following is a specification, reference being had to the accompanying drawing, forming part thereof.

Figure 1 is a side elevational view of the box; and Figure 2 is a top plan view of the same, both views showing my new design. The shading is intended to indicate contrasting colors namely, red and gold.

I claim:

The ornamental design for a hexagonal cosmetic box, as shown and described.

In testimony whereof I affix my signature.

HELENA J. TITUS.
